UNITED STATES PATENT OFFICE

JOHN A. BORLAND, OF ST. PAUL, MINNESOTA, ASSIGNOR TO BORLAND TRANSPORTATION AND MANUFACTURING COMPANY, A CORPORATION OF ARIZONA

BLOCK SIGNAL CHECKING DEVICE FOR RAILROADS

Application filed July 6, 1931. Serial No. 548,742.

- The present invention relates to a block signal checking device for railroads. Most railroads at present are equipped with electrical signal means to indicate to a train crew the presence of another train on the same section of track as that being entered by their train, and also to indicate any break in the electrical connection of the rails in said section.
- 10 In order to be effective, these signals, and their operating circuits, must function with the utmost reliability, and it is therefore necessary to check them frequently, and to maintain them in the best possible condition.
- 15 An object of the present invention is to improve and simplify the checking of block signal apparatus, and the rail circuits therefor.
- In order to attain this object, there is provided, in accordance with one feature of the invention, a carriage provided with motive power to propel it along a track, and having wipe brushes in electrical contact with the track over which the device is being operated, 20 the mechanism being provided with interchangeable electrical circuits by means of which various conditions of the track, and the associated signals can be tested to determine their operativeness.
- 25 These and other features of the invention will be more fully brought out in the following description and the accompanying drawings, wherein:
- Figure 1 is a plan view of a mechanism embodying the present invention.
- Figure 2 is a sectional view on the line 2—2 of Figure 1.
- Figure 3 is an end view of the mechanism shown in Figure 1.
- 40 Figure 4 is a view in perspective of a conducting bar and a pair of rail contacting brushes.
- Figure 5 is a view in side elevation of a wheel and a rail contacting brush, a portion 45 of the housing of the brush being broken away to show the construction thereof.
- Figure 6 shows side and front views, respectively, of a brush housing and associated brush, portions of the housing in each view
- being broken away to show the construction thereof; and
- Figure 7 is a schematic view of an electrical circuit embodied in the device.
- Referring to the drawings in detail, a carriage A, the construction of which is not material to the invention, is here shown as having axles 1 and 2 at the ends thereof, with flanged wheels 3 rotatably mounted on the axles. A compartment 4 is mounted longitudinally of one side of the carriage for containing the driving motor and the electrical apparatus necessary for the carrying out of my invention. This compartment is disposed longitudinally along one side of the carriage so as to bring most of the weight of the device over the wheels on one side so as to facilitate tipping the carriage when it is necessary to remove it from the track.
- Pivotedly mounted in bearings 5 adjacent each of the axles are a pair of rods 6 and 7 the end portions 8 of each of these rods being bent to lie at substantially right angles to the central portions of the rods. These rods are each provided with brush housings 13 mounted on each of the bent end portions 8 thereof. An operating handle 9 is provided on each of the rods 6 and 7 and each of these handles is provided with a hand grip portion 10 pivotally connected thereto, said hand grip portion being provided with a pin, not shown, adapted to enter openings 11 in a segment 12 secured to the carriage to retain the operating handles 9 in adjusted position.
- In each of the brush housings 13 is mounted a brush 14 which may be of carbon, the brush being of a size to have a slidable fit within the housing 13. A coil spring 15 is mounted within the housing 13 above the brush 14 to exert a resilient downward pressure on the brush. Each brush is provided with a plurality of transverse parallel apertures 16, in any one of which may be inserted a pin 17, the ends of which ride in longitudinally disposed slotted apertures 18 in the sides of the housing members 13 to limit the downward movement of the brushes when the

brushes are raised out of contact with rails 19 upon which the device is mounted.

The device may be propelled by a gasoline motor 20 of a conventional type, having driving connection with one of the wheels as by means of a sprocket chain 21 in a well known manner. A clutch, not shown, of any suitable type, is embodied in the motor and may be operated by a lever 22 which projects upwardly through a slotted opening 23 in the top of the compartment 4. An instrument panel 24 is mounted in a recessed central portion 25 of the compartment 4, so that the instruments mounted in said instrument panel will lie entirely below the surface of the top of the compartment. A hinged door 26 is mounted on one side of the recess 25 so that it may be swung over when desired to cover the recess and protect the instruments when not in use. This door may be swung downwardly to the position shown in Figure 3, when it is desired to use the instruments.

The interior of the rear portion of the compartment 4 may be sub-divided, as illustrated in Figure 2 to provide individual compartments for various pieces of apparatus employed in carrying out the present invention. A horizontal partition 27, which may be of heavy sheet metal, is secured in position below the instruments mounted upon the instrument panel 24 and the portion of the compartment below this longitudinally disposed partition is divided transversely by a vertical partition 28 so as to divide this space into two compartments, one 29 of which, may be used as a battery compartment, and the other 30 of which may be used to house a relay 31, and a second similar relay directly behind the one shown in Figure 2 and which, therefore, does not appear in the drawings. The electrical wiring is omitted from Figure 2 for the purpose of simplifying the drawings. The method of wiring is clearly illustrated, however, in Figure 7.

In using the present device it is necessary to have a complete set of instruments and circuit controls for each rail, so that each rail may be tested separately. A complete set of instruments and associated circuits and other apparatus for the testing of one rail are illustrated in Figure 7. A similar circuit arrangement and a duplicate set of apparatus are required for the testing of the other rail.

In this circuit a three-position switch 33 is provided. This switch is adapted to electrically connect pairs of adjacent contact points. The switch 33 has ends of electrically conductive metal, which ends are insulated from each other and from the central portion of the switch, as by means of insulation 34 so as to prevent a flow of electrical current across this switch. The specific type of switch is not material to the invention and any suitable switch for selectivity connecting the various pairs of conductors, as herein-

after described, would be suitable. The contact points 35 and 36 and the contact points 37 and 38 are arranged, when connected with each other, by means of the ends of the switch 33 to complete an electrical circuit from a battery 39 through a rail from one brush B-73 to the other brush B-74. This circuit will be later described in detail.

The next two pairs of contact points to be connected by the armature, namely the points 40 and 41 in one group, and 42 and 43 in the other, when connected by means of the switch 33, are arranged to complete an electrical circuit from one brush B-73 to the other brush B-74 on the same rail, and, when the rail over which the device is traveling is charged with direct current electricity, to detect a break in the electrical circuit through the rail. When the switch 33 is moved to electrically connect contact points 40 and 44 in one group, and 43 and 45 in the other, a circuit is completed from the brush B-73 through various instruments to be hereinafter set forth in detail, to the other brush B-74. This circuit is designed to detect a break in the electrical connections in the rail when the rail is charged with alternating current electricity, and this circuit, therefore, is connected through a separate portion of a relay coil designed for alternating current and also through alternating current recording instruments.

Before considering the arrangement of each of the circuits above referred to, the various pieces of apparatus and recording instruments employed in the circuits will be described. The instruments illustrated in the upper right hand portion of Figure 7 comprise a direct current volt meter 48, an alternating current volt meter 49, an alternating current ammeter 50, and a second direct current ammeter 51. A rheostat 52 is provided to control the intensity of the current, and a relay 53 is constructed with the coil thereof in two sections, one section of which is used in the alternating current circuits, and the other in the direct current circuits. Signal mechanisms such as an electrically actuated horn 54 and an electrical signal lamp 55 are also provided. A magnetically actuated paint spraying valve 56 is provided with an operating coil 57 having an armature 58 pivotally mounted upon a support 59 and adapted to be attracted by the magnetism of the coil 57 when said coil is energized to open the valve 56. This valve is connected as by means of a pipe 60 to a hermetically sealed tank, not shown, containing a quantity of paint under pressure, and a second pipe 61 is mounted with its open end adjacent a rail so that when the valve 56 is opened paint from said tank will be forcibly ejected through the pipe 61 onto the rail or ties to indicate actuation of the apparatus and thus indicate 120 125 130

a defective condition of the rail at the point marked.

An electrical generator 62 is mounted to be driven by the gasoline drive motor 20 and a switch 63 is mounted to selectively connect the generator to charge the storage battery 39 when the switch is in dotted line position and to disconnect the generator and to connect the storage battery to the circuit when the switch 39 is in the solid line position as shown in Figure 7.

Referring now to the circuits in detail, it is assumed first that the switch 33 is in position to connect the contact points 35 and 36 and the points 37 and 38.

Battery circuit

With the switch in the above position, the device is intended to complete an electrical circuit from the battery 39 through the section of rail between the front and rear brushes B-73 and B-74 on each rail to hold the alarm mechanism in unoperated position, and upon encountering a break in the rail between the brushes to energize the alarm system. The switch 63 is moved to the solid line position shown in Figure 7 to disconnect the generator 62 and to connect the battery 39 to the circuit. From one terminal of the battery 39, a conductor 64 is connected to a second conductor 65 which is connected to the contact point 36. From here the switch 33 connects across to the contact point 35 and from thence a conductor 66 is connected to the direct current winding of the relay coil 53. The other end of this portion of the winding is connected by means of a conductor 67 to the rheostat 52 from which a conductor 68 is connected to the direct current ammeter 50 which is not employed in this circuit, but does not interfere with the operation of the circuit. From D. C. ammeter 47, wire 69 leads to A. C. ammeter 50. From this alternating current ammeter 50 a conductor 70 is connected to a conductor 71 which is connected to a brush B-73. From here the circuit extends across through the rail 72 to the other brush B-74 from whence a conductor 75 is connected to the switch 63 and thence to the negative side of the battery.

It will be seen that as long as this circuit is complete (and it is apparent that a break in the rail 72 will break this circuit), the relay 53 will remain energized holding the armature 76 of the relay in the dotted line position. As long as the relay is held in the dotted line position the alarm circuit, which is indicated in heavy black lines on the drawings, will remain open, since with the relay in this closed position, the conductor 64 from the positive side of the battery will be connected through the relay armature to a conductor 77 which is connected to the contact point 42 and by means of a conductor 78 to contact point 45. Inasmuch as neither of

these contact points is connected to the switch 33, with the switch in the present referred to position, it is apparent that the alarm circuit will not be complete. Assuming, however, that a broken rail is encountered between the brushes B-73 and B-74, the circuit through the relay 53 will be broken, releasing the armature 76, whereupon the spring 79 will draw the armature 76 to the solid line position shown in Figure 7.

This will complete a circuit from the positive side of the battery 39 through conductor 64, through the armature 76 of the relay, to a conductor 80 which is connected to the contact point 38. The contact point 38 is disconnected by the switch 33 to the contact point 37 whence a conductor 81 is connected to a conductor 82 which in turn is connected to conductors 83 and 84, which are connected, respectively, to the sound emitting apparatus 54 and the lamp 55. The conductor 82 is connected to the coil of the relay 57. The other sides of the sound emitting apparatus, lamp and coil are connected by conductors 86, 87, and 88 to a conductor 89 which is connected to the direct current ammeter 51 from whence a conductor 90 is connected to a conductor 91 connected to a conductor 96 which is connected through the switch 63 and a conductor 92 to the negative side of the battery. From the conductor 82, a conductor 100 is connected to the D. C. volt meter 48, and thence a conductor 91 is connected through switch 63 and conductor 92 to negative battery. This completes the circuit through the alarm apparatus and also energizes the paint valve 56 which sprays a quantity of paint onto the rail to indicate the point at which the alarm mechanism was energized.

Direct current rail circuit

Assume next that it is desired to test a section of rail which is energized with direct current. For this operation, the switch 33 will be moved to connect the points 40 and 41, and the points 42 and 43.

When the testing mechanism is passing over normal, unbroken track, it will be apparent that the current in the track circuit will flow through the rails and there will be no tendency for the current to flow through a circuit connected to the brushes B-73 and B-74. However, should the carriage pass over a break in the rail 72, the rail current, being unable to pass this break, will flow through the circuit between the brushes.

The direct current rail circuit is arranged as follows, the switch 33, being set as above described: From brush B-74, conductor 75 is connected to a conductor 96, to the contact point 40 across the switch 33 to the contact point 41, through a conductor 93, the conductor 66, the direct current portion of the relay coil 53, the conductor 67, the rheostat 52, conductor 68, the ammeter 47, the con-

ductor 69, the alternating current ammeter 50, which is not affected by the passage of the direct current of this circuit, but does not interfere therewith, and thence through the conductors 70 and 71 to the other brush B-73.

As above pointed out, no current will flow through this circuit except when the track is energized with direct current and the track 10 circuit is broken between the brushes B-73 and B-74. This being so, the relay 53 will remain normally unoperated, as indicated in solid lines in Figure 7, when the mechanism is passing over unbroken rails. From the 15 normally closed contact of the relay 53, conductor 80 is connected to terminal point 38 and as the switch 33 is not in contact with this terminal point, the alarm circuit will be de-energized, when the relay 53 is open. Upon 20 energizing of the relay 53, however, the alarm circuit will be energized, current flowing from the positive terminal of the battery 39, through the conductor 64, the armature 76, the conductor 77, to the contact point 42, 25 thence across the switch 33 to the contact point 43, thence through the conductor 82, the signal means 54 and 55 and the paint valve relay 57, as above described for the first circuit and thence through the conductor 89 to 30 the ammeter 51 and thence through conductors 90 and 91 to negative battery.

Alternating current rail circuit

For similarly testing the rails when they 35 are charged with alternating current, the switch 33 is moved to connect the points 40 and 44 and the points 43 and 45.

As above explained, no current will flow through the circuit when passing over un- 40 broken rails, but when a break in the rail circuit is brought between the brushes B-73 and B-74, current will flow from the brush B-74, through conductor 75, conductor 96 to terminal point 40, thence across the end 45 of the switch 33, to contact point 44, through a conductor 95, to the alternating current winding of the coil 53, thence through the conductor 67, through the rheostat 52, the conductor 68, through the direct current 50 voltmeter 47, which is not material to the present circuit, but does not interfere with the flow of the alternating current there- 55 through, through the conductor 69, the alternating current ammeter 50, thence through the conductors 70 and 71 to the brush B-73.

As there is normally no flow of current through this circuit, as above set forth, the relay 53 will be normally unoperated. Therefore, the relay armature 76 will be normally 60 in contact with the conductor 80 and as this conductor is connected to the terminal point 38 with which the switch 33 is not in contact, the alarm circuit will be normally unoperated.

Upon operation of the relay 53 caused by a

break in the rail circuit between the brushes B-73 and B-74, the alarm circuit will be energized through conductors 77 and 78, contact point 45, across the end of the switch 33, to contact point 43, thence through conductor 82 and the remainder of the alarm circuit, as 70 above set forth.

For most test purposes the rail circuit will be used for testing the mechanism, being set to the required position, as hereinbefore de- 75 scribed, depending upon whether the rails are charged with alternating or direct cur- rent.

Should there be more than one break in a rail circuit under test, however, it is apparent that the test circuit would not be energized in passing over one of these breaks, since the rail circuit would also be open at the other break. When a double break is suspected, therefore, the test will be conducted by means of the first of the above described 80 circuits, namely, that in which the switch 33 connects the contacts 35 and 36 and the contacts 37 and 38.

The mechanism comprises a simple and positive means of locating and making broken rails and other open connections in block signal rail circuit and which performs these operations while moving over a track under its own motive power.

I claim:

1. A railway rail circuit tester, comprising a wheeled carriage, a pair of contact members longitudinally spaced apart and adapted to engage a rail upon which the carriage is supported, and an electrical circuit interconnecting said rail contact members and adapted to be energized by a flow of electricity through said circuit, said rail normally constituting a shunt across said contact members to prevent a flow of electrical current through said circuit.

2. A railway rail circuit tester, comprising a wheeled carriage, a pair of contact members longitudinally spaced apart and adapted to engage a rail upon which the carriage is supported, an electrical circuit interconnecting said rail contact members and adapted to be energized by a flow of electricity through said circuit, said rail normally constituting a shunt across said contact members to prevent a flow of electrical current there- 110 through, a second circuit normally out of electrical connection with said brushes and having a source of electrical current therein, selective switch means adapted to disconnect said first circuit and connect said second circuit to said contact members, alarm means normally held in an inoperative position by a flow of current from said source of electrical current, through said rail, and means adapted to energize said alarm means upon an interruption of said flow of current.

In testimony whereof I affix my signature.

JOHN A. BORLAND.
